X-RAY TUBE

Zed J. Atlee, Elmhurst, Ill., assignor to General Electric X-Ray Corporation, Chicago, Ill., a corporation of New York

Application April 25, 1942, Serial No. 440,516

7 Claims. (Cl. 250—149)

My invention relates in general to electronics and has more particular reference to an X-ray generator having an anode providing an electron target comprising target material deposited on the anode in the form of a metallic film.

An important object of the present invention resides in providing an electronic anode having an electron target comprising a thin film of metal deposited on the surface of a suitable anode base; a further object being to provide an anode for an X-ray generator having a target surface formed by condensing target material produced by thermal evaporation upon the target surface of the anode; a further object being to provide means for depositing the target forming material on the anode after the same has been assembled and sealed in the envelope of the generator.

Another important object is to provide means for changing or replenishing the target material on the anode of an electronic device from time to time during the service life of the device.

Another important object is to provide for the application of target material upon the target surface of an anode by heating a supply of target material in order to vaporize the same and then directing the vaporized material upon the target surface of the anode whereby to condense the vaporized material upon the target surface of the anode.

Another important object is to provide an X-ray generator having an anode forming a target surface and controllable means for applying target material to said surface; a further object being to provide a generator having target material mounted therein, preferably in the cathode structure of the generator, in combination with means operable outwardly of the generator for applying the target material to the anode; a further object being to provide for the selective application of different target materials on the anode from time to time; a still further object being to provide a generator particularly well adapted for use in X-ray diffraction analysis by virtue of the ability selectively to condition the anode for operation with different materials in place thereon as electron targets.

The foregoing and numerous other important objects, advantages and inherent functions of the invention will become apparent as the same is more fully understood from the following description, which, taken in connection with the accompanying drawing, discloses a preferred embodiment of the invention.

Referring to the drawing:

Figure 1 is a side view, partially sectionalized, of an X-ray tube embodying my present invention;

Figure 2 is an enlarged sectional view of the anode and cathode of the device shown in Figure 1;

Figure 3 is a sectional view taken substantially along the line 3—3 in Figure 2; and

Figure 4 is a perspective view of parts of the device.

Analysis of materials may be accomplished by exposing material to be analyzed to X-rays and observing the resulting X-ray diffraction spectrum on a sensitive screen or film.

The radiation of X-rays from a generator produces a continuous, or "white," spectrum the characteristic wave length and intensity distribution of which depends upon the operating potential of the generator and upon the characteristic "line" spectrum of the material employed in the generator as an electron target. Every target material has its own characteristic X-ray spectrum, which is independent of the operating potential of the generator above a minimum voltage, which minimum voltage also is characteristic of the particular target material involved.

Any suitable target material may, of course, be employed for X-ray diffraction analysis, provided that the material of the target, and hence its characteristic "line" spectrum, is known; otherwise, the lines caused by the target material in the spectrograph of the material being examined may be mistaken for lines supposedly caused by the material under examination. The choice of a proper target material for X-ray diffraction analysis depends to a great extent upon the type of specimen being examined, the particular examination technique employed, and the kind of information sought; and it is obvious that, regardless of technique or the nature of the specimen under examination, a prerequisite for accurate analysis is the accurate predetermined of the spectrum characteristics of the target and hence of the X-rays produced by the generator. It will be apparent that X-ray diffraction analysis may be facilitated by providing means for substituting different target materials on the anode of a generator in order thus to make the generator capable of producing selectively X-rays having desired spectral characteristics corresponding with any one of a selection of target materials, whereby the generator may be used for examining a wide range of specimens.

In order thus to facilitate the examination of

materials by X-ray diffraction, I have provided an X-ray generator having means incorporated therein for changing, at will, the target material carried by the anode for receiving electron impingement in the generation of X-rays at the target; and to illustrate the invention, I have shown on the drawing an X-ray tube 11 comprising an anode 13 and a cathode 15 in facing relationship and enclosed within an hermetically sealed and evacuated envelope 17 and having 10 suitable electrical connections extending through the envelope for supplying the anode and cathode with electrical power from a suitable external source. The cathode 15 may comprise an electron emitting filament 25 mounted on a head 19 which in turn is supported and sealed upon a re-entrant envelope portion comprising a hollow stem 21. The filament itself may be supported at its opposite ends on stems, including a stem at one end of the filament extending through a duct 20 in the head 19 and supported in suitable clamp means behind the head whereby to space and insulate the stem from the head. At the other end of the filament, the support stem may pass through a similar duct, or the stem may be press-fitted in a socket in the head whereby to electrically connect the filament on the head. Conductors 23 for energizing the electron emitting filament 25 are sealed in and may extend through the stem 21 and outwardly of the envelope at one 25 end of the generator for connection with a suitable external source of power for energizing the filament for electron emission. As shown, one conductor 23 is connected with one of the filament stems while the other conductor is connected to the head.

It will be noted that the filament is of elongated character and is supported in a groove 27 formed in the cathode head whereby electrons emitted by the filament, when energized, will be focused upon the facing or target end 31 of the anode. The anode, near its target remote end, is formed with a shoulder to which is sealed a disk or washer 33 having an annular edge forming a glass-to-metal seal 35 with a re-entrant envelope portion 41, the anode having an extension 43 projecting outwardly of the envelope through the washer 33 and being fitted with inlet and outlet conduits 45 for the circulation of a cooling fluid into the anode and adjacent the target end thereof for cooling the anode.

The envelope 17 preferably, though not essentially, comprises hard glass and is formed with conical embossments fitted with window-panes 47 of lime glass, beryllium, or other suitable window-pane material substantially transparent to X-rays, the windows 47 being preferably located on the envelope opposite the target end of the anode in position to project X-rays emanating from the target end of the anode outwardly of the envelope. The cathode head also is preferably provided with a skirt 49 encircling the target end of the anode and formed with openings 51 for the transmission of useful X-ray beams from the anode to and through the windows 47. The tube also is preferably enclosed in an annular sleeve 53, which may comprise split parts suitably clamped together around the window portion of the envelope, the sleeve 53 being provided with openings 55 for receiving the window carrying envelope projections. If desired, the sleeve 53 may be formed of material opaque to X-rays for the purpose of confining therein all X-rays except the beams which emanate from the anode

5 through the openings 51 in the cathode skirt, the windows 47 and the sleeve openings 55.

The anode 13 comprises a base of suitable material, such as copper, for supporting an electron target thereon at the target end 31 of the anode. I may employ any suitable target material, such as chromium, cobalt, nickel, iron, copper, manganese, vanadium, molybdenum, tungsten or titanium.

The anode 13 preferably is first finished to a desired size and shape and is then assembled and sealed in the envelope. Means is provided within the envelope of the generator for applying target material to the target surface 31 of the anode, said means being controllable from outside of the envelope; and the invention contemplates means operable to apply any selected one of a number of different target materials upon the target surface, said materials being applicable successively and at any time throughout the service life of the generator, whereby the character of the anode target, and consequently the X-ray spectral characteristics of the generator, may be changed at will.

To this end, I provide within the envelope a supply of each of the target materials; and in connection with each such supply, I provide means, controllable outwardly of the envelope, for depositing the target material in the form of a thin film thereof upon the target surface 31 of the anode. As shown, the target material is mounted in the envelope in the form of a wire or rod 57, said rod being supported in a slot-like cavity 59 preferably formed in the cathode head 19 and opening on said head in a direction facing toward the target surface 31 of the anode. The rod of target material 57 is embraced within and supported by a preferably helically disposed heating filament 61 which, with the rod 57, is disposed within the cavity 59. The filament 61 may be mounted on stems 62 at its opposite ends, including a stem at one end of the filament extending through a duct in the head 19 and supported in suitable clamp means behind the head whereby to space and insulate the stem from the head. At the other end of the filament, the support stem may pass through a similar duct, or the stem may be press-fitted in a socket in the head whereby to electrically connect the filament on the head. Suitable conductors, including a conductor 63, and another conductor which may be separate or which may be the head connected filament conductor 23, are dielectrically connected with the heating filament 61 through its support stems, the conductors extending thence outwardly of the envelope through the hollow re-entrant stem 21 and through suitable hermetic seals on said stem, as is the case with the conductors 23. By connecting the heating filament conductors with a suitable source of electrical power outwardly of the envelope, through suitable current control devices, the filament 61 may be heated to any desired temperature necessary to vaporize the target material of the rod 57. The vaporized material so generated in the cavity 59 will be expelled therefrom, as indicated in dotted lines in Figure 2, through the open side of the cavity 59 and thus directed upon the target surface 31 of the anode, and will condense thereon and adhere thereto in the form of a thin film of target material 65.

The film of target material 65 may be made to cover a definite area of the target surface 31 by shaping the notch or slot 59 substantially in accordance with the configuration of the area of

the target surface to be coated with target material. In this connection, where the electron emitting filament 25 of the cathode comprises an elongated element, as shown in Figure 3 of the drawing, electrons emitted by said filament will impinge upon the target surface 31 within an elongated target area, which area necessarily should be covered by the layer of target material 65. This may be accomplished by making the slot 59 parallel and of substantially the same length as the elongated cavity which contains the cathode filament 25, and by making the rod of target material 57 substantially the same length as the filament 25.

The film of target material should be applied to the anode while the latter is at a temperature causing the vaporized target material readily to condense and adhere upon the target surface of the anode. The temperature of the anode, however, should not be high enough to promote solution of the vaporized material with the material of the anode base to any degree more than necessary to allow the target material to "wet" and adhere on the anode base, as otherwise the target material in the film 65 may become contaminated by the material of the base should alloying occur to any extent throughout the thickness of the film. For this reason, it is desirable that the anode base be held at a temperature but slightly higher than normal room temperature while the film 65 is being applied. The film 65, of course, may be applied by depositing superposed layers of material on the anode base.

In order to facilitate the assembly of the rod 57 and filament 25 in the slot 59 which, it will be noted, is inclined in the head 19 to face the medial portions of the target surface 31, the head may be formed with a demountable segment 67 which, when in place, defines one side of the cavity 59. By removing the segment 67, the filament and rod 57 may be easily assembled in position on the head 19. After the filament and rod are thus assembled on the head 19, the segment 67 may be replaced and secured on the head by suitable preferably threaded fastening members.

It is thought that the invention and its numerous attendant advantages will be fully understood

from the foregoing description, and it is obvious that numerous changes may be made in the form, construction and arrangement of the several parts without departing from the spirit or scope of the invention, or sacrificing any of its attendant advantages, the form herein disclosed being a preferred embodiment for the purpose of illustrating the invention.

The invention is hereby claimed as follows:

10. 1. An X-ray generator comprising a sealed envelope, an electron emitting cathode and a co-operating anode base forming a target surface in said envelope facing said cathode, said cathode having a head provided with a cavity in spaced relation with the electron emitting portion of the cathode, a supply of target material in said cavity, heating means for vaporizing said target material, means for energizing the heating means from a controllable source outwardly of the envelope, and means for applying vaporized target material and condensing same as a thin film on said target surface.
15. 2. An X-ray generator as set forth in claim 1, wherein the target material is in rod-like form.
20. 3. An X-ray generator as set forth in claim 1, wherein the means for vaporizing the target material comprises a heating filament.
25. 4. An X-ray generator as set forth in claim 1, wherein the means for vaporizing the target material is mounted in the cavity.
30. 5. An X-ray generator as set forth in claim 1, wherein the cavity is provided with an opening toward the medial portions of said target surface and said supply of target material and the means for vaporizing the same are supported in said cavity.
35. 6. An X-ray generator as set forth in claim 1, wherein the cathode head has a demountable section defining a side of the cavity whereby to facilitate the assembly of the target material and the means for vaporizing the same in said cavity.
40. 7. An X-ray generator as set forth in claim 1, wherein a plurality of unlike target materials are supported within the envelope so that a selected target material may be applied to said target surface at will during the service life of the generator.
